(57) **CLAIM**

The ornamental design for a structure hanger, as shown.

DESCRIPTION

FIG. 1 is a perspective view of a structure hanger, according to one embodiment of this invention;

FIG. 2 is a side view of the structure hanger, as shown in FIG. 1;

FIG. 3 is a side view, opposite the side view shown in FIG. 2, of the structure hanger;

FIG. 4 is a front view of the structure hanger, as shown in FIG. 1;

FIG. 5 is a rear view of the structure hanger, as shown in FIG. 1;

FIG. 6 is a top view of the structure hanger, as shown in FIG. 1;

FIG. 7 is a bottom view of the structure hanger, as shown in FIG. 1;

FIG. 8 is a perspective view of the structure hanger, according to another embodiment of this invention;

FIG. 9 is a side view of the structure hanger, as shown in FIG. 8;

FIG. 10 is a side view, opposite the side view, shown in FIG. 9, of the structure hanger;

FIG. 11 is a front view of the structure hanger, as shown in FIG. 8;

FIG. 12 is a rear view of the structure hanger, as shown in FIG. 8;

FIG. 13 is a top view of the structure hanger, as shown in FIG. 8; and,

FIG. 14 is a bottom view of the structure hanger, as shown in FIG. 8.
